UNITED STATES PATENT OFFICE.

BENJAMIN GEORGE CLAUDE STEPHENS, OF AUCKLAND, NEW ZEALAND.

ELECTRIC-IRON PLUG.

Application filed January 30, 1925, Serial No. 5,753, and in New Zealand September 19, 1924.

This invention relates to the ordinary types of plugs used in conjunction with electric irons for the attachment of the cord conductor wires thereto, and which plugs 5 in their general form are made with two contact sockets that respectively fit on to resistance terminal pins upon the iron.

The invention has been devised with the object of embodying means within such a 10 form of plug that will cause the current to the iron to be automatically cut off should the iron become overheated through neglect or any other cause. These means are of such a nature that a switch interposed in 15 the conductors to one of the contact sockets, remains closed so long as the usual and safe temperatures are not exceeded, but which switch is positively opened immediately the 20 temperature reaches the degree predetermined upon and for which the appliance is set.

The said switch is adapted to be controlled 25 by a bi-metallic strip composed on the well known principle of strips of laminated metals having different co-efficients of expansion and contraction and which strip is disposed within the plug so that one end 30 is made fast to and in thermo contact with one of the contact sockets. The heat from 35 the iron will thus be conveyed by contact conductivity to the strip to cause its free end to move laterally should the heat become sufficiently great.

In its normal state the free end of the strip 40 holds a spring controlled switch in place to keep the circuit closed, but when such end moves laterally for a specified distance, it frees the switch so that the spring may 45 actuate to open the circuit.

The invention also embodies as an alternative, a construction of the spring controlled switch the features of which provide for the automatic testing of the thermostatic control in that the switch is designed to open a 45 short period after the iron current is turned on and then is manually closed again and held closed so long as the ordinary working temperature is not exceeded.

A suitable manner of carrying out the 50 invention is illustrated in the accompanying drawings, in which:

Figure 1 is a front elevation of the plug.

Figure 2 is a face view of the rear or base half of the plug showing the fittings 55 attached thereto.

Figure 3 is a side elevation of the plug, the

wall being broken away to expose the fittings.

Figure 4 is an underneath plan of the 60 plug.

Figure 5 is a horizontal section thereof, taken on the line 5—5 of Figure 2.

Figure 6 is a detail view of one of the sockets and certain attached parts.

Figure 7 is a detail view showing in elevation, the switch as made in the alternative manner mentioned, and in its first closing position.

Figure 8 is a similar view, partly in section, showing the switch in its second closing position.

Figure 9 is a plan thereof.

The plug is formed upon the usual general lines prevailing in the construction of these appliances; that is, with a body of vulcanite 75 or other insulating material made in two halves, a rear or base half 7 and a front half or cover 8, constructed to fit face to face together and to be fastened by means of transversely extending screws 9. The adjacent faces of these two parts are recessed to receive the several fittings embodied in the plug and these comprise two socket tubes 10 and 11 that extend upward from openings 12 in the lower end of the plug and are secured 85 to the rear half 7 thereof by screws 13. These sockets are made in the usual split style to adapt them for passing respectively over the terminal pins of the electric iron and for gripping them.

The socket 10 is connected with a conductor strip 14 leading to the upper end of the plug and which is secured to the plug at its upper end by means of a terminal screw pin 15 to which also one wire of 95 the ordinary cord 16 is connected.

The second socket 11 is also connected with a conductor strip 17 but this strip is made in two portions, an upper portion 18 being provided and affixed to the plug so that its lower end overlaps the top of the portion 17 with a distance between. The said upper portion 18 is secured by means of a terminal screw 19 to which the second wire of the cord 16 is connected. So long therefore as the gap between the portions 17 and 18 remains unbridged, current cannot flow to 100 the iron.

A switch lever 20 is provided and is pivoted in a frame bearing 21 affixed to the 110 rear half of the plug. This lever extends across the width of the plug and at its inner

end has affixed to it a metallic bridging block 22 which is so shaped as to be adapted to pass in between the ends of the two portions 17 and 18 of the second conductor strip and to bridge them electrically, or to disengage said portions and thus break the contact. The lever tends to rock in a direction to effect such disengagement, due to the action of a spring 23 (Figure 5) which surrounds the pivot pin 24 of the lever and bears upon the inner arm of said lever, or to other equivalent means. When the lever is freed, this spring will act and rock the lever to open the switch formed thereby.

15 The other end of the lever passes out through a slot 25 formed in the joint between the two plug halves and is made with a finger knob 26 on its end so that it may be actuated from the outside to close the switch. When the lever is in the closed position, the knob 26 lies within a hood 27 formed in the plug edge to receive it and to protect it against being accidentally engaged to turn the switch, in the use of the iron.

20 25 The lever and its bearings are effectively insulated from the conductor strip 14 to prevent any short circuiting through the lever, or the lever may be itself formed of non-conducting material.

30 35 The lever switch is retained in its raised position to close the circuit by means of the bi-metallic strip 30 that is positioned to extend up within one edge of the plug so that its upper end engages beneath the bridging block 22 while its lower end is affixed by brazing or like operation to a copper or other metallic bracket piece 31. This bracket piece is shaped to extend across the rear and across the outer side of the

40 45 socket 11 and also has the socket made fast to it so that a thermo unit is produced composed of the socket, the bracket and the strip 30. The strip 30 is also so disposed that its upper end is adapted to move across the width of the plug in the movements to which it is subject under varying heat conditions.

The bi-metallic strip 30 is so made that bending movement takes place when the strip is subjected to a heat greater than that of the usual working temperatures of the iron. Should the temperature of the iron therefore increase abnormally, the heat is conveyed by direct contact from the iron terminal pin to the socket 11 and from it to the strip 30. The strip will then bend outward, freeing the bridge block 22 and permitting the spring 23 to act and rock the lever to break the contact. The current will 55 60 thus cease to flow.

Accurate adjustment of the amount of movement in the strip necessary to free the block 22 is obtained by means of the small adjusting screw 33 passing through one portion of the bracket piece 31 and engaging

the outside face of the strip at a point above the strip's attachment to such bracket piece. A small aperture 34 is left in the joint between the two halves of the plug to permit of access to this screw.

70 In the construction of the switch lever 20 shown in Figures 7 to 9, its bridging end 22 is forked, and between the fork arms a tumbler piece 35 is pivoted upon a pin 36. Such tumbler piece has a downwardly extending nose 37 on its outer end and is so constructed and pivoted that the inner end is adapted to fall and to project the nose 37 out a short distance beyond the extremities of the fork arms 22 of the switch lever. 80 The tumbler piece is prevented from falling too far at its inner end by means of a pin 38 extending across the fork arms of the switch lever, and the amount of fall to be allowed it may be accurately adjusted by 85 means of the screw pin 39 that is screwed down through such end to engage the said cross pin 38.

90 The thermostatic strip 30 is made on its inside face with a tooth 30^a positioned near its top end, such tooth having a square upper end and an inclined inside face. The strip in this case is made so that its upper end will bend outwards a small amount as the iron heat works up to its safe working heat, as for instance after a period of ten or fifteen minutes from turning on the current, and will bend further out as the heat exceeds the predetermined safety point.

95 100 When the iron is cold and the switch 20 is closed, the ends of the fork arms 22 of the switch lever as they pass up, will brush aside the top of the strip 30 and will rest on such top, the nose 37 of the tumbler piece engaging the face of the tooth 30^a and being turned in thereby, as in Figure 7. As the iron heats and the strip 30 turns out, it will free the switch lever, so that the switch will open in the manner before described. Then on closing the switch manually, with the strip still 105 in its partially bent position, the nose 37 which has fallen outwards owing to the dropping of the tumbler piece, will engage and rest upon the top of the tooth 30^a of the strip as shown in Figure 8 and thereby hold the switch in the closed position, until the heat of the iron reaches such a temperature as to move the strip out enough to free such nose, when the switch will again open.

110 115 120 This construction thus makes provision for the automatic testing of the control, and in addition provides, by the first control, for the current being almost immediately turned off should it be turned on and the iron then left and forgotten, while the second control ensures that no overheating through neglect or other cause will take place after the iron has been heated to its working temperature.

125 130 The thermostatic strip 30 may have attached to it, a pin 40 that projects trans-

versely from its outer surface through between the body parts 7 and 8 to the outside and which pin may be used to draw the strip out to open the switch whenever it is desired 5 to do so.

I claim:—

1. In an electric switch, the combination of a conductor; a pivotally-mounted switch lever; a second conductor embodying a pair 10 of stationary, structurally-separate members having their mutually-adjacent ends spaced apart to form a gap to be bridged by one end of said lever; a spring tending to swing said lever into non-bridging position; and 15 a thermostatic element adapted to engage and retain the lever in bridging position and to automatically disengage the same when abnormally heated.

2. In an electric switch, the combination of 20 a conductor; a pivotally-mounted switch lever having a forked end adapted to engage said conductor; a spring tending to swing said lever end away from the conductor; a tumbler pivotally mounted in the lever fork 25 for automatic movement independently of and relatively to said lever; and a thermostatic element having a tooth adapted to engage said tumbler and thereby retain the lever in conductor-engaging position, and to

automatically release the tumbler when ab- 30 normally heated.

3. An automatic switch, according to claim 2, in which the tumbler has a depending nose that normally projects beyond the forked end of the switch lever and is adapted 35 to be directly engaged and disengaged by the tooth on the thermostatic element.

4. An automatic switch, according to claim 2, in which the tumbler carries an adjustable stop for engagement with a cross-pin mounted 40 in the forked end of the switch lever to limit the pivotal movement of the tumbler in one direction.

5. An automatic switch, according to claim 2, in which the tumbler is provided at one 45 end with a depending nose and at the other end with an adjustable depending stop; said nose normally projecting beyond the forked end of the switch lever and adapted to be directly engaged and disengaged by the tooth 50 on the thermostatic element; and said stop adapted for engagement with a cross-pin mounted in the forked end of the switch lever to limit the pivotal movement of the tumbler in one direction. 55

In testimony whereof, I affix my signature.

BENJAMIN GEORGE CLAUDE STEPHENS.
